LOOSE-LEAF BINDER BOOK

Saul Shaler, Jackson Heights, Long Island, N. Y.

Application April 14, 1939, Serial No. 267,798

18 Claims. (Cl. 40—104)

This invention relates to books and is directed more particularly to loose-leaf binder books wherein means is provided for opening the book to any selected page in a simple and efficient manner and without necessitating the fingering of individual pages. The book of the present invention may be employed as a telephone or other index, register, perpetual calendar, docket, etc., and when so used has been found to possess

5 a high degree of efficiency and convenience.

10

I am aware that it has heretofore been suggested to provide index devices adapted to be opened at predetermined points, but all of these devices have been of a bulky and cumbersome nature. They have generally embodied a relatively heavy base to serve as a support for leaves hingedly superimposed thereon, with an overlying pivoted cover or lid carrying sheet engaging devices by which a greater or lesser number of

15 such sheets may be selectively engaged so that, when the lid is raised, the thus attached sheets are lifted therewith from the base to expose the predetermined underlying sheet. They have been expensive from the standpoint of manufacture

20 and are intended primarily for desk use.

25

The present invention, in contradistinction, embodies a simple, economical construction which may be conveniently carried around in the pocket of the user, as any other form of loose-leaf binder book, and useful for ready reference. The book requires no heavy, cumbersome base or support and the movement of the pages of the book is independent of the book covers.

30

Speaking generally, the book of the present invention, in its preferred form, comprises a back and associated covers of any suitable material or materials, which conveniently may be of paper, cardboard, leather or imitation leather, or a combination thereof. A loose-leaf binder element is mounted at the back of the book to which the covers are hinged or with which they are formed integral and this loose leaf binder element supports the pages of the book in the usual manner on split rings which may be sprung open or closed for the addition or removal of pages as desired. The binder element, which is of metal, supports a page operator on which is slidably supported a page selector, adapted to be manually moved into the desired position to select the particular page which the operator desires. Through the manipulation of the page operator the book may be opened to the selected page. The page operator may, if desired, be spring-actuated to move it into page opening position and means

35

40

45

50

55

is preferably associated with the page selector

to lock the page operator in the position which it normally takes when the book is closed. When the page selector is moved to page selecting position, it is by this movement unlocked, so that the page operator can be either manually or spring actuated to open the book to the page selected. In this respect, the present invention differs greatly from all prior indices or registers wherein a selection of a page is first accomplished by a member mounted on a cover or lid and wherein the latter is thereafter released or unlocked, so that movement of the cover or lid will move the sheet.

An important feature of this invention resides in the fact that it embodies, in the main, standard loose-leaf binder parts to which certain adjuncts or accessories are added to facilitate the opening of the book to a predetermined page. In fact, the invention may be so constituted that it may be detachably associated with any appropriate loose-leaf binder book without requiring change or modification of the structure of the latter. This is possible because the page operating devices of this invention are supported on the metal binding element of the book, independently of the book covers and function wholly independently of such covers. This permits me to mount on the interior of either or both of said covers, conventional collapsible pockets in which cards and other loose papers may be carried and to which access may be had without movement of the page operating devices. I am also thus enabled to supplement the indexed pages of the book by a number of memo pages to be used or referred to without requiring movement of said page operating devices.

35

40

45

50

55

The invention thus provides a more complete arrangement than heretofore produced in connection with mechanical indices or the like and accomplishes all the results of prior devices as well without necessitating cumbersome and bulky structures embodying numerous and complicated working parts which are liable to get out of order or break. My device, in contradistinction, is extremely simple and because of its use of standard construction may be manufactured and sold with marked economy over prior devices of this general class.

The present invention also provides a highly efficient construction for a perpetual calendar or docket, wherein opposing faces of adjacent pages of the book have delineated thereon spaces corresponding to the twelve months of the year, while each two opposing faces of such adjacent pages are appropriate to one particular day of

60

65

one of the twelve months thus delineated. With this arrangement a person opening the book to a particular day of the month will have before him the corresponding day of every month of the year with manifest advantages, particularly in business and professional fields, as will be hereinafter more specifically referred to.

Features of the invention, other than those adverted to, will be apparent from the herein-
10 after detailed description and claims, when read in conjunction with the accompanying drawings.

The accompanying drawings illustrate different practical embodiments of the invention, but the construction therein shown is to be understood as
15 illustrative, only, and not as defining the limits of the invention.

Figure 1 is a perspective view showing a loose-leaf binder book embodying the present invention in opened position.

20 Figure 2 is a section on the line 2—2 of Figure 1.

Figure 3 shows a page layout appropriate for use as a perpetual calendar or docket.

25 Figure 4 is a perspective view of a simplified form of the invention.

Figure 5 is a fragmental detailed perspective view of one bracket of Figure 4.

Referring to the drawings, 1 and 2 indicate the front and back covers of a book, which may be
30 integral with or hinged to the back 3. These parts may be of any suitable material or a combination thereof. The back cover 2 is somewhat wider than the front cover 1 of the book to provide a projecting portion indicated at 4 in Figure
35 1 and on this projecting portion is a column of characters 5 in the form of letters, such as the letters of the alphabet or numerals indicating the days of the month and/or other indicia presently explained.

40 The back of the book 3 supports a page binder, indicated generally at 6, which may be of the substantially conventional form used in loose-leaf binders and comprising a hollow metal housing 7 supporting split rings 8, conventionally
45 spring actuated as is common in loose-leaf binders to be snapped open and closed for the purpose of engaging or disengaging the perforations 9 of a plurality of book pages 10.

These pages 10 are cut away at their upper and
50 lower edges in the vicinity of the binder 6 to provide space for mounting brackets in the form of twin lugs 11 which may be attached to or stamped from the housing 7 of the binder. Through these twin lugs are passed rivets 12 and
55 on these rivets are pivotally supported the opposite ends of a page operator 13. This operator may be made from a strip of sheet metal bent into substantially U-shaped, bail form with right angle corners and of a size to extend around
60 the margins of the free edges of the several pages of the book, so that the longitudinal portion 14 of the page operator is straight and parallel to the lateral free edges of the pages and spaced closely with reference thereto.

65 On this longitudinal portion 14 is slidably supported a page selector 15. The page selector 15 has its upper and lower edges bent over the corresponding edges of the portion 14, as indicated at 16, so as to mount the selector for sliding
70 movement thereon. In practice, the selector is preferably pre-formed and slipped onto the portion 14, while tongues 17 at the end of this portion are bent into the dotted line position indicated in Figure 1, after which these tongues 17 are bent back into the plane of the stock from

which they are formed in order to lock the selector against disengagement.

The selector is provided with a suitable finger piece or pieces 18 bent up from the selector, and a pointer 19 and page lifter 20 are similarly formed and respectively point in opposite directions. The pointer is so positioned that it will point in the direction of the free edge of the cover and will thus be cooperative with the column of figures or letters 5 when the book is closed. The page lifter extends in the opposite direction, so as to be directly adjacent the inner face of the back cover 2 and underlie all of the pages of the book when the book is closed. The several pages of the book are cut away at 21 along their vertical free edges for progressive distances from the top down, so that successive portions of the consecutive pages are presented for cooperative relation with the page lifter 20, when the book is closed, and those portions of the pages which project beyond the edges of the next adjacent pages, bear appropriate designations 22, corresponding to the letters, figures or other indicia 5 of the back cover.

I preferably mount on the inner face of the back cover a retainer 23, so shaped and located that, when the book is closed, the page selector 15 may be moved into a position to engage beneath the offset end 24 of this retainer for the purpose of locking the page operator in closed book position. When this locking means is provided, the cut away portions of the pages and the designations of the column 5 should be such that the pointer will indicate a locked position and no particular page will be selected. The retainer 23 is shown as positioned about midway of the height of the book, although it may be positioned near either the top or the bottom if desired. The retainer is particularly useful if there is associated with the page actuator, springs 25. These springs are coiled about the rivets 12 with one end 26 of each spring engaging the binder housing 7 and the other end 27 engaging a tongue 28 stamped from the page operator 13. When these springs are employed, they tend to move the page operator into open position, but are held in restraint when the page lifter is engaged with the retainer 23. The page lifter 20 and the offset portion 24 of the retainer may be respectively provided with a projection 29 and a depression 30 to preclude inadvertent movement between them when they are engaged.

In Figure 1 the pages of the book are shown as ruled in such manner as to render the book appropriate for use as a telephone index or the like and consequently the characters 5 and 22 comprise letters of the alphabet, with a designation 31 indicating "locked" position of the page lifter. In Figure 3 the ruling of the pages is such as to render the book useful as a perpetual calendar or docket. Here, each page is divided into six spaces, so that facing pages will collectively embody twelve spaces consecutively designated according to the months of the calendar year, while the designations 22 correspond to the numerical days of the month. The column 5 in this case is numbered 1-31 to correspond and the indication 31 "locked" remains the same.

When the book is opened to any particular page, in the construction of Figure 3, it will disclose, for example, the 15th day of the month for each and all of the twelve months of the year. This arrangement possesses many advantages, particularly in the business and professional fields

where one must keep track of future events or obligations.

The book of the present invention may be made either with or without the springs 25 and these springs are preferably omitted when the arrangement of Fig. 3 is employed and they may of course be likewise omitted with the layout of Fig. 1. In any event the springs have no connection with either of the covers. They are merely interposed between the binder 6 and the page operator 13. The covers are associated with the binder in the usual manner and have no connection with the springs nor have they any connection with the page operator 13, except when the page lifter is locked to the retainer 23 which is mounted on the back cover.

In use, the book is closed in the usual manner and, if the springs 25 are embodied in the construction, the selector is moved into a position to engage the page lifter with the retainer and thus the page operator is locked to the back cover although the pages themselves may be freely turned if desired. When the book is to be opened the finger piece 18 is gripped between the thumb and forefinger, and the page selector is slid along the portion 14 of the page operator until the pointer 19 registers with the designation in the column 5 which indicates the page desired. If no springs 25 are incorporated, the operator then opens the book by manually swinging the finger piece in a direction to open the book, the front cover 1 having been previously opened or not as desired for it has no connection with the page operator. As the page operator is swung over on the pivots of the binder 6, the page lifter 20 will engage the proper page and cause the book to open at the right place.

If, however, the springs 25 are incorporated, the user need not manually swing the page operator for, after it is released from the retainer, it will tend to open the book, and this before the selection of the desired page has been accomplished. Consequently, it is essential for the user to hold the finger piece after he has unlocked the page lifter from the retainer and until he has moved the page selector to the point necessary to select the desired page, and if the finger piece is then released, the springs will open the book without any manipulation of any part of the structure. Mere release by the fingers initiates the operation. The purpose of the retainer, therefore, when used with the springs, is merely to hold the page operator in a position to operate such pages as may be manually selected after the page operator has been unlocked. In other words, the springs do not move the pages upon the unlocking of the page lifter or until the point of separation of the pages has been thereafter manually determined. Hence when the book is in normally closed position, the page lifter is always left in the same locking position from which, by sliding movement, it is released and moved to a page selecting position for the purpose of subsequently opening the book at the selected place when the operator's fingers are removed from the finger piece. When the pages are moved, they simply swing about the rings of the binder 6 on which they are supported and the movement of the pages from one position to the other is accomplished by the page operator 13 which is mounted on and carried by the binder 6. The cover 1 has nothing to do with the operations of the member 13 and said cover 1 may, if desired, be opened and left opened all the time without in anywise

affecting the operations of this part. The back cover 2 merely serves to carry the column of identifying indicia 5 and the retainer 23.

In practice, I preferably include at the back of the book and between the last page and the cover a sheet of cardboard or other material 31 which may be mounted on the rings 8 or secured to the back cover and this serves as a spacer to leave a space between the last page and the cover in which the page lifter may travel without engaging with any of the pages, as the selector is slid along the portion 14 of the page operator.

In the constructions of Figures 4 and 5, I have shown a simplified form of construction without the locking means and without springs associated with the page operator. In this construction, the present invention is illustrated to be associated with a conventional loose-leaf binder. Thus, in Figures 4 and 5, the metal binder 6 carrying rings 9, back 3 and the covers 1 and 2 are standard and form part of the conventional loose-leaf binder of commerce.

In associating the invention with such a conventional construction, the page operator 13 with its page selector 15 is made as in the preceding figures, but, instead of being connected to brackets struck up from or permanently mounted upon the metal binder 6, as in the previous figures, it is mounted on brackets 32, each of which is provided at its base with a spring clip 33, so shaped and proportioned that it can be sprung over the metal binding 6 of the loose-leaf binder. The opposite ends of the page operator are pivoted to the brackets 32 by eyelets 34, so that by simply springing the spring clips 33 into engagement with a metallic binder of a loose-leaf binder, the present invention may be associated therewith. The indexed pages 10 employed in this book are the same as described in connection with the previous figures, although the corners of the pages adjacent the binder need not be cut away as much if at all.

The operation of the indexed pages 10 is wholly independent of both of the covers 1 and 2 and I may thus provide on the interiors of either one or both of the front and back covers a collapsible envelope 35 adapted to hold detached papers for ready reference. Between the front cover and the indexed pages 10 I may also incorporate into the book a number of additional memorandum pages, price lists or catalogue 36 supported by the rings 8 and access may be had to these pages or to the envelope without operation of the page operator and by simply opening the front cover while the book remains otherwise closed.

Loose-leaf binders are standardized and embody binders of relatively few standard sizes, so that no difficulty is experienced in making spring clips appropriate to these sizes.

It is to be noted that the book of the present invention opens through 180 degrees, so that both facing pages of the book may be read with equal facility, whereas in previous designs of index, it has been common to open the book 65 for only approximately 90 degrees, which makes it difficult to read the upstanding page, much less to write thereon.

The foregoing detailed description sets forth the invention in its preferred practical form, but the invention is to be understood as fully commensurate with the appended claims.

Having thus fully described the invention, what I claim as new and desire to secure by Letters Patent is:

1. A book comprising a back, front and back covers hingedly connected to the back, a binder mounted on the interior of the back and supporting a plurality of pages for swinging movement, said pages being progressively cut away along their free edges to provide a succession of projecting portions, a page operator pivoted to the binder for swinging movement with the pages, and a page selector, mounted on the page operator and manually slidably thereon, to engage with a selected page, whereupon swinging movement of the page operator will open the book to such page.
2. A book comprising a back, front and back cover hingedly connected to the back, a binder mounted on the interior of the back and supporting a plurality of pages for swinging movement, said pages being progressively cut away along their free edges to provide a succession of projecting portions, brackets positioned adjacent the opposite ends of the binder, a bail-like page operator pivotally supported on said brackets and loosely embracing the free edges of the pages, and a page selector slidable on said page operator and having a projecting page lifter movable therewith into cooperation with any particular page projection, whereupon pivotal movement of the page operator will open the book to the selected page.
3. A book comprising a back, front and back covers hingedly connected to the back, a binder mounted on the interior of the back and supporting a plurality of pages for swinging movement, said pages being progressively cut away along their free edges to provide a succession of projecting portions, a page operator pivoted to the binder for swinging movement with the pages, a page selector, mounted on the page operator and manually slidably thereon, to engage with a selected page, whereupon swinging movement of the page operator will open the book to such page, and resilient means operatively connected with the page operator to swing the latter in a page opening direction after the page selector has been moved into cooperative relation with a selected page.
4. A book comprising a back, front and back covers hingedly connected to the back, a binder mounted on the interior of the back and supporting a plurality of pages for swinging movement, said pages being progressively cut away along their free edges to provide a succession of projecting portions, a page operator pivoted to the binder for swinging movement with the pages, a page selector, mounted on the page operator and manually slidably thereon, to engage with a selected page, whereupon swinging movement of the page operator will open the book to such page, resilient means operatively connected with the page operator to swing the latter in a page opening direction after the page selector has been moved into cooperative relation with a selected page.
5. A book comprising a back, front and back covers hingedly connected to the back, a binder mounted on the interior of the back and supporting a plurality of pages for swinging movement, said pages being progressively cut away along their free edges to provide a succession of projecting portions, a page operator pivoted to the binder for swinging movement with the pages, a page selector, mounted on the page operator and manually slidably thereon, to engage with a selected page, whereupon swinging movement of the page operator will open the book to such page, and means for holding said resilient means in restraint when the book is closed and the page selector is in a predetermined position.
6. A book comprising a back, front and back covers hingedly connected to the back, a binder mounted on the interior of the back and supporting a plurality of pages for swinging movement of the page operator will open the book to such page, resilient means operatively connected with the page operator to swing the latter in a page opening direction after the page selector has been moved into cooperative relation with a selected page, and means mounted on the back cover and on the page selector for holding said resilient means in restraint when the book is closed and the page selector is in a predetermined position.
7. A book comprising a back, a front cover hinged to one side of the back, a back cover hinged to the other side of the back, a loose-leaf binder mounted on the interior of the back, and page selecting means mounted on the binder.
8. A book comprising a back, a front cover hinged to one side of the back, a back cover hinged to the other side of the back, a loose-leaf binder mounted on the interior of the back, pages supported by the loose-leaf binder, and page selecting means also mounted on the binder, said book being adapted to open through 180 degrees.
9. A book comprising a back, a front cover hinged to one side of the back, a back cover hinged to the other side of the back, a loose-leaf binder mounted on the interior of the back, and page selecting means, mounted on the binder, the front cover of the book being hingedly movable independently of the page selecting means.
10. A book comprising a back, a front cover hinged to one side of the back, a back cover hinged to the other side of the back, a loose-leaf binder mounted on the interior of the back, indexed pages supported on the loose-leaf binder, additional pages also mounted on the binder, and page selecting means for the indexed pages also mounted on the binder, said front cover and additional pages being hingedly movable without requiring movement of the page selecting means.
11. A book comprising a back, front and back covers hingedly connected to the back, a binder mounted on the interior of the back and supporting a plurality of pages for swinging movement, a page operating member pivoted to said back for swinging movement, and means for locking the page operating member to the back cover, the front cover being pivotally movable with respect to the back cover and the page operating member while the page operating member remains locked against pivotal movement to the back cover.
12. A book comprising a back, front and back covers hingedly connected to the back, a binder mounted on the interior of the back and supporting a plurality of pages for swinging move-

ment, a page operating member pivoted to said back for swinging movement, a page selector mounted on the page operating member, and means on the back cover engaging the page selector for locking the page operating member to the back cover, said front cover being movable from closed to open position while the page operating member remains locked to the back cover.

10 13. A book comprising covers, a page operator mounted for swinging movement between the covers, pages also mounted between the covers and operable selectively by the page operator, and a spacing member also pivotally movable between the covers for spacing the rearmost page from the back cover.

14. A book comprising a loose-leaf binder, covers hingedly associated therewith, and pages carried by the binder, in combination with page 20 operating means detachably supported on the binder and selectively operable when actuated to select a predetermined page.

15. A page turner for loose-leaf binders comprising a page operating frame adapted to embrace the periphery of the free edges of the pages of a loose-leaf binder book, means carried by

said frame for detachably mounting the same for pivotal movement upon said binder, and means also carried by the frame to select and engage a predetermined page of the book to open the book to such page when the page operating frame is pivotally moved with respect to the binder on which it is mounted.

16. An accessory for loose-leaf binders comprising page selecting and turning means including spring clips adapted to be detachably engaged with a binder and pivotally supported thereon, and a page turning frame carrying a manually operable page selector.

17. A book comprising a back, covers hingedly connected to the back, and a page turning frame 15 mounted independently of the covers and having thereon a slide carrying a page selector, a locking member and an indicator.

18. A book comprising a back, covers hingedly connected to the back, and a page turning frame 20 mounted independently of the covers and having thereon a slide carrying a page selector, a locking member and an indicator, all integral with and forming part of the slide.

25

SAUL SHALER.
